UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

SEAM RUBBING.

Application filed April 16, 1921. Serial No. 461,793.

To all whom it may concern:

Be it known that I, FREDERICK M. FURBER, a citizen of the United States, and resident of Revere, in the county of Suffolk and 5 State of Massachusetts, have invented certain Improvements in Seam Rubbing, of which the following description, in connection with the accompanying drawings, is a specification, like reference characters on 10 the drawings indicating like parts in the several figures.

This invention relates to seam-rubbing or seam-flattening machines, and is illustrated as embodied in a machine in which 15 a heated seam-pressing member flattens a seam against a seam-supporting roll.

When the edges of two pieces of material, such as fabric or leather, are sewed together, the marginal portions beyond the seam stand 20 out at right angles to the surface of the material; and it is often desirable to smooth or rub the seam, to lay these marginal portions flat. In order to do this, it is first necessary to separate the two marginal portions, and turn them over, whereupon they 25 may be ironed flat. The devices heretofore used for separating these portions, or "opening the seam," sometimes failed properly to perform their function, in that a careless operative might guide both of the marginal portions on one side of the separating or 30 opening member, causing the machine to jam, or turning both portions in the same direction. Moreover, difficulty has been found in imparting a permanent "set" to 35 the seam by the use of previously-known seam-pressing members.

The object of this invention is to provide 40 an improved seam-rubbing machine which obviates these difficulties by the use of novel seam-opening and seam-pressing devices.

One feature of this invention is to be 45 found in a novel seam opening device comprising a seam-supporting guide plate, a separator or plow to separate and turn down the marginal portions beyond the seam, and guide members having surfaces parallel to the surfaces of the plow. The 50 illustrated guide members are spaced from the plow, on either side, by distances equal

to the thickness of the marginal portions joined by the seam. They extend ahead of the plow, to receive the unseparated seam, and are there spaced from one another by 55 a distance equal to the sum of these thicknesses. This provides positive guidance of the seam, and makes jamming impossible by reason of both marginal portions crowding on the same side of the plow. There 60 is provided, moreover, novel and improved means for adjusting the guide members for seams of different thickness.

A further feature of the invention is to be found in a novel seam-pressing member 65 which co-operates with a power-rotated seam supporting and feeding roll to flatten the opened or separated seam. This member is yieldingly pressed against a seam supported by the roll, and is heated by a stationary electric heating unit. According to one form of the invention, mechanism is provided for imparting to this heated 70 pressing member, while in engagement with the seam, a rubbing or ironing motion. According to alternative forms, in addition to such a rubbing motion, the forward end of the pressing member is given a pounding motion by suitable actuating mechanism. Such seam-pressing members impart a permanent set to the flattened seam in a very 75 efficient manner.

Further features of the invention are to be found in an improved casing enclosing 80 the actuating mechanism, and having an 85 opening to permit access thereto, which is covered by a plate carrying the seam-opening device; in novel means to depress the power-rotated roll to permit withdrawal of a flattened seam, and adjustably to fix the 90 upper position of the roll; and in various combinations and specific constructions more fully described in the following detailed description and pointed out in the 95 appended claims.

In the drawings,

Fig. 1 is a front elevation, partly broken away;

Fig. 2 is a cross-section through the machine at right angles to Fig. 1;

Fig. 3 is a bottom plan view of the seam opening device;

Fig. 4 is a section on the line 4—4, Fig. 2; Fig. 5 is a section on the line 5—5, Fig. 2; Fig. 6 is a section on the line 6—6, Fig. 2; Fig. 7 shows an alternative construction 5 of the seam-flattening member; and

Figs. 8 and 9 show a second alternative construction.

The illustrative machine is enclosed in a casing 10, carrying an adjustable bracket 10 12, on which is mounted a motor 14, which drives the main shaft 16.

Driven from the main shaft 16 by bevel gears 20 is a vertical shaft 22, which rotates a horizontal shaft 24 through a worm gear 15 26. The outer end of shaft 24 carries a bevel gear 28, which meshes with a co-operating bevel gear 30, which is keyed to a vertical shaft 32 to permit it to be slid up and down relatively to gear 30 while 20 constantly driven thereby.

The shaft 32 is carried by a slide 34, movable vertically in the casing 10 as shown in Fig. 2. It is yieldingly raised to upper position by a spring 36, whose tension may 25 be varied by turning the adjusting bolt 38, and it may be depressed by pulling downwardly on link 40 by means of a suitable treadle, not shown, and treadle rod 42. The upper position of slide 34 may be adjusted 30 by means of a set-screw 44, which engages a pin 46 carried by the slide. The pin passes through a slot 48 in the casing 10.

Supported by the slide 34 is a feeding roll, or rotary work support 50, constantly driven 35 from shaft 32 by bevel gear 52. Fixedly mounted on the slide 34, in co-operative relation to the work support 50, is a guide plate 54, which supports the work, as shown in Figs. 4 and 5, during the opening of the 40 seam, and delivers it to the work-support 50 for flattening. By this arrangement the rotary work-support 50 and the guide plate 54 may be depressed by the treadle rod 42, to permit withdrawal of a flattened seam 45 which, because of its form, cannot be passed entirely through the machine.

An opening in the front of the casing 10, to permit access to the enclosed mechanism, is closed by a plate 60, held by clamp-screws 62. Mounted on this plate is a member 64, vertically adjustable by turning a threaded device 66, and held in adjusted position by a screw-and-slot clamp 68. The lower end of member 64 is formed into a plow 70, for opening a seam as shown in 50 Figs. 4 and 5.

Two seam guides 80 are mounted, one on each side of the plow 70, to co-operate therewith in opening a seam. These guides are 60 pivotally mounted on member 64, at 82, and are pressed together by a spring 84. Between them is a threaded stem 86, on which is a conical nut 88, the forwardly-projecting portion of which may be, as illustrated, split and contracted, to hold the nut 65

firmly in adjusted position regardless of the vibration of the machine. By screwing the nut inwardly the conical portion forces the guides 80 apart against the tension of the spring 84, thus permitting adjustment of 70 the position of the guides. For convenience of illustration, the right-hand seam guide 80 is broken away in Fig. 2.

The novel form of these guides is shown clearly in Fig. 3. They are spaced from the 75 plow 70 to provide two channels A and B for the two margins being separated and turned ready for flattening. Forwardly of the plow, the guides 80 project somewhat toward one another, to provide a narrowed 80 channel C, equal in width to the sum of the widths of channels A and B.

In previous forms of plow-and-guide seam-opening devices of this general character, the channel at C has not been narrowed 85 to be equal to the sum of channels A and B. Therefore, in such forms, when channels A and B are of the correct width to guide the margins of a seam being opened, as shown in in Figs. 4 and 5, the channel corresponding 90 to C is too wide to support the unopened seam properly. A careless operative may therefore allow the entire unopened seam to be deflected in one direction by the plow, either into the channel corresponding to A 95 herein, or the one corresponding to B. This results in jamming the work in the machine, and ruining the work. By the arrangement described above, the channel C is just wide enough, when properly adjusted, to permit 100 ready insertion of the seam, which is therefore necessarily guided in such a manner that it must invariably be opened properly, and jamming is impossible.

The seam-flattening member is illustrated 105 in one modification at 100 in Fig. 2, mounted for a rubbing or ironing motion only. In alternative forms it is shown at 200 in Fig. 7, and at 300 in Fig. 8, mounted for both rubbing and pounding motion.

In the rear end of the movable member 100 (or 200 or 300) is a recess 102, in which is a sleeve 104 (Fig. 6) carrying a heat unit 106 to which current may be supplied through suitable lead wires 108. The sleeve 104, 110 and therefore also the unit 106, are held stationary during the movement of member 100 by a bracket 110. To reduce the heat lost through conduction by bracket 110, holes 115 are provided therein, to reduce the conducting area to a minimum.

Member 100 is integral with, or secured to, a supporting projection 112, in which holes may be provided, if desired, to minimize heat loss. This projection is secured 125 to a cross-piece 114 between links 116, mounted on spindles 118, supported by links 120, pivotally mounted in casing 10 on a spindle 122. Links 120 are constantly oscillated by 130 a lever 124 pivoted to projections 126 there-

on at 128. Lever 124 terminates in a sleeve 130, surrounding an eccentric 132 on shaft 16.

Links 116, carrying member 100, are constantly urged about spindles 118 as an axis by a spring 134 connected at one end to a lug on lever 124 and at its other end to a cross-piece 136 between the upper end of links 116. This maintains member 100 in yielding engagement with a seam on the work-support 50, as it is given a rubbing or ironing oscillatory motion about spindle 122 as an axis, by lever 124 and eccentric 132.

It is desirable that the heated ironing or rubbing member 100 should not come in contact with the work-support 50 when there is no seam thereon. To this end the right-hand spindle 118 (Fig. 1), which is fixedly secured to link 116, carries an arm 138, having a roller 140 at its outer end, which may follow an adjustable cam member 142. If there is a seam on the work support 50, the rubbing member 100 is lifted thereby against the tension of spring 134, so that roller 140 does not engage the cam member 142. If no seam is present, the roller and cam hold member 100 just out of engagement with the work-support 50, causing it to follow, in its oscillatory motion, a path in a circle concentric with the work-support or feed roll 50.

The member 100 is cut away at 144, to facilitate the entrance of the seam, and also to leave at 146 the shortest possible seam-engaging surface which will flatten the seam effectively. By reducing this surface to a minimum, the heat consumed is less, and moreover a greater portion of member 100 is left to act as a heat reservoir, lessening the fluctuation in temperature.

In Fig. 7 is shown an alternative construction of the seam-flattening means. For convenience of illustration this figure shows only the upper portion of the feed roll and the modified parts. All other parts of the machine are the same as previously described.

According to this modification, a member 200 is provided, cut away at 244 to provide a hammer head 242 and an ironing portion 246 which has the same function as the ironing portion 146 of member 100. Member 200 is suspended from spindle 122 by a link 216 provided with a fork 220 which bears member 200 by a pivotal mounting 218. A spring 248 constantly presses against fork 220 and a lug 250 on member 200, thus maintaining the ironing portion 246 constantly in yielding engagement with a seam during the pounding motion of the hammer head 242.

This pounding motion is provided by a link 226, pivoted to link 216 at one end and to the frame 10 at 228 at the outer end and by forming the upper end of link 216 into a sleeve surrounding an eccentric 232, rotated

from shaft 16 by pulleys 230—240 and belt 224. This mechanism moves the hammer head 242 in an elliptical path to pound a seam against the work-support 50. At the same time, in combination with the constantly-acting spring 248, it imparts an ironing or rubbing motion to portion 246 of member 200.

In Figs. 8 and 9 is shown another alternative construction of the seam-flattening member. In this form, the seam-flattening member 300 has an ironing portion 346, heated by the unit 106, and yieldingly held, by spring 348 bearing on lug 350, in engagement with a seam on the work support 50. The forward portion of the portion 346 is forked, and a rotary pounding portion or hammer 342 is mounted in the fork on shaft 318, which is rotated from shaft 122 by belt 332 and pulley 352. As shown clearly in Fig. 9, the seam is pounded by portion 342 and ironed down by portion 346 of the seam-flattening member 300.

In operation, a seam is placed on the guide plate 54, and the marginal portions are guided into channel C between guides 80. These guides and plow 70 open the seam, as shown in Fig. 5. Thereafter the seam is fed forward by the power-rotated feed wheel and work support 50, while the seam is flattened as shown in Fig. 6, by member 100, 200 or 300, as the case may be.

While I have described in detail an illustrative embodiment of my invention, it is not the intention to limit its scope thereby, or otherwise than by the terms of the claims.

Having described my invention, what I claim as new and desire to secure by Letters Patent of the United States is:

1. In a seam-rubbing machine, in combination, means to open a seam, a power-actuated support and feed device for the opened seam, and a heated, power-actuated member to flatten the opened seam against the support as it leaves the seam-opening means.

2. In a seam-rubbing machine, in combination, plow and guide members for opening a seam, a power-rotated support for the opened seam, and a heated power actuated device to flatten the seam against the support and co-operate with the support in feeding the seam.

3. In a seam-rubbing machine, in combination, a plow and guides for opening a seam, a guide plate for the seam being opened, a power-rotated supporting roll to receive the opened seam, a heated iron to rub the seam against the roll, and a lever to oscillate the iron back and forth to flatten the seam.

4. In a seam-rubbing machine, in combination, means to open a seam, a support for the seam opened thereby, a heated iron to press the seam against the support, and mech-

- anism to move the iron back and forth to flatten the seam, and to feed it across the support.
5. In a seam-rubbing machine, in combination, a ridged plate to guide a seam, means to open a seam guided thereby, a power-rotated work-support to receive the opened seam therefrom, a member to flatten the opened seam against the work support by a combined pounding and rubbing motion, and means to heat said member.
6. In a seam-rubbing machine, in combination, a seam-support, means to open a seam passing on to said support, and a heated member to pound the opened seam against the support, and to feed it thereover.
7. In a seam-rubbing machine, in combination, a work support, a guide plate to position a seam relatively to the support, a blunt plow spaced from the guide plate to open a seam passing therebetween, and guide members spaced from the plow a distance approximately equal to the thickness of one margin making up the seam, and spaced from one another in front of the plow a distance equal to the thickness of both margins.
8. In a seam-rubbing machine, in combination, a seam-flattening element, actuating mechanism therefor, a cover enclosing said mechanism and having an opening giving access thereto, a plate covering said opening, and a seam-opening device mounted on said plate.
9. In a seam-rubbing machine, in combination, a guide plate having a ridged surface arranged to enter the acute angle between two flexible sheets joined by a seam, a blunt plow having its longitudinal axis approximately parallel to the ridge on said surface and arranged to open the seam, and guide members each spaced from the side of the plow a distance equal to the thickness of one of the flexible sheets, and spaced from each other in front of the plow a distance not exceeding the thickness of both of the sheets.
10. In a seam-rubbing machine, in combination, a guide plate to support a seam, and a blunt end plow and guide members spaced therefrom and arranged to open a seam supported thereby, and constructed to provide a space for the passage of the seam which is constricted immediately in front of the plow to compensate for the thickness of the blunt end of the plow and be uniform throughout in cross-section and approximately equal to the thickness of the seam.
11. In a seam-rubbing machine, in combination, a seam support, a member having one portion spring-pressed against the support to rub a seam thereagainst and another portion oscillated to pound the seam against
- the support, and means to heat the rubbing portion of said member.
12. In a seam-rubbing machine, in combination, a power-rotated seam support, a member to pound and rub a seam thereagainst, and means to heat said member. 70
13. In a seam-rubbing machine, in combination, a seam support, a member to pound a seam thereagainst and tending to feed it thereover, and means to heat said member. 75
14. In a seam-rubbing machine, in combination, a seam support, a heated member arranged to rub a seam thereagainst, and means to move said member back and forth in engagement with the seam in both directions. 80
15. In a seam-rubbing machine, a seam support, a heated member to flatten a seam thereagainst, a lever to impart a rubbing motion to said member, and a cam to prevent the heated member from engaging the support when there is no seam thereon. 85
16. In a seam-rubbing machine, in combination, a power-rotated seam support, a heated, power-actuated member to flatten a seam thereagainst, and means to move the support away from said member to permit removal of a seam which has been flattened. 90
17. In a seam-rubbing machine, in combination, a power-rotated roll to support a seam, means to flatten a seam thereagainst, gearing to rotate said roll, and a lever to move the support away from the seam-flattening means while constantly maintaining it in operative connection with said gearing. 95
18. In a seam-rubbing machine, in combination, a hammer to flatten a seam with a combined pounding and rubbing action having one portion intermittently to pound against the seam and another portion constantly to rub against the seam, and means to heat the seam to set it in flattened position. 100
19. In a seam-rubbing machine, in combination, a seam-ironing member having a recess therein, a lever to impart a rubbing motion to said member, a heating unit in said recess, and a support to maintain said unit stationary. 110
20. In a machine of the class described, in combination, a reciprocating work-engaging member having a recess therein, a sleeve in said recess, a support to maintain said sleeve stationary, and an electrical heating unit in said sleeve and held stationary thereby while heating the reciprocating member. 115
21. In a machine of the class described, in combination, a reciprocating work-engaging member having a recess therein, an electrical heating unit in said recess, and a support to maintain the heating unit stationary, said support having holes there- 120
- 125
- 130

- through to reduce the amount of heat conducted thereby.
22. A seam-flattening member having one end formed into a hammer and the other end into a seam-ironing device, and having a recess for a heating unit in the seam-ironing end.
23. In a seam-rubbing machine, in combination, a work supporting guide plate arranged to engage the reverse side of a seam and guide it into the machine, and seam guiding members to co-operate therewith, spaced apart to permit the seam to pass therebetween, and single means for simultaneously adjusting said members to guide seams of different thicknesses.
24. A seam-opening device comprising a plow for opening a seam, and a guide on each side of the plow extending in front thereof, each of said guides being spaced from the plow a distance approximately equal to the thickness of one of the marginal portions joined by the seam, and approaching each other in front of the plow to be spaced from each other by a distance no greater than the sum of the thicknesses of the two marginal portions making up the seam.
25. A seam-opening device comprising a plow for opening a seam, and a guide on each side thereof adjustable toward and from the plow, said plow and guides being constructed and arranged to provide passages for a seam before and after it is opened, the cross-section of the passage for the unopened seam being equal to the sum of the cross-sections of the passages for the opened seam irrespective of variations in the adjustment of the guides.
26. In a seam-rubbing machine, in combination, a plow for opening a seam, a seam-guide on each side of the plow and a device for simultaneously adjusting said guides relatively to the plow.
27. In a seam-rubbing machine, in combination, a plow for opening a seam, a guide on each side thereof, a spring to press said guides toward the plow, and an adjustable member to cam said guides apart against the tension of the spring.
28. In a seam-rubbing machine, in combination, a rotary work-support to feed a piece of work containing a seam to be acted upon, means to flatten the seam against the support, means to depress the support to permit withdrawal of work between the flattening means and the support, and mechanism to rotate the work-support.
29. In a seam-rubbing machine, in combination, a work support, a seam-flattening member to press a seam against the support, and a lever to rub the seam-flattening member back and forth in engagement with the seam.
30. In a seam-rubbing machine, a roll to support a seam, a movable member to flatten a seam against the roll, and a cam to prevent said member from engaging the roll when no seam is thereon.
31. In a seam-rubbing machine, in combination, a support for a seam, a member to flatten a seam against the support, a lever to pound the forward end of said member against the seam, and a spring to press the rear end of said member against the seam.
32. In a seam-rubbing machine, in combination, a seam support, and a member to flatten a seam thereagainst, and means to impart to said member a combined pounding and rubbing motion.
33. In a seam-rubbing machine, a rotary work-support, a frame carrying said work-support, a guide-plate for a seam carried by the frame, means to depress the frame to allow work to be withdrawn from the machine, and mechanism to rotate the work-support whether or not the frame is depressed.
34. In a seam-rubbing machine, a seam-flattening member, links pivotally supporting said member, a power operated lever to oscillate the links to impart a rapid rubbing motion to said member, and a spring constantly urging said member to turn about its pivot into engagement with a seam which is being flattened.
35. In a seam-rubbing machine, in combination, a seam-rubbing member, oscillating links pivotally supporting said member, a lever to oscillate the links to impart a rubbing motion to said member, a spring urging said member to turn about its pivot into engagement with a seam, and a plate preventing undue turning of said member if no seam is present.
36. In a seam-smoothing machine, a hammer to flatten a seam, and mechanism to impart to one end of said hammer a pounding motion and to the other end an ironing motion, to flatten a seam and iron it into flattened position.
37. In a seam-rubbing machine, in combination, a seam-flattening member, a spring to press one end of said member against a seam, and a lever to pound the other end of said member against the seam.
38. In a seam-rubbing machine, in combination, a seam-flattening member, a spring to press one portion of said member against a seam, a lever attached at one end to another portion of said member, a link connected to the lever intermediate its ends, a strap on the other end of the lever, and an eccentric in the strap, by which arrangement the second portion of the seam-flattening member is given a pounding motion in an elliptical path.

39. In a seam-rubbing machine, in combination, a seam-flattening member having one end formed into a hammer for pounding a seam, the other end formed into a smoothing iron to press a seam, and having a cut-out portion between the hammer and the smoothing iron, a spring to maintain the smoothing iron end of said member in engagement with a seam, and mechanism to impart a pounding motion to the hammer end.
40. A seam flattening member of metal, one end of which is formed into a hammer, a cut-out portion behind said hammer, and an ironing portion behind the cut-out portion.
41. In a seam-rubbing machine, in combination, seam-guiding members, and a single device for simultaneously adjusting said members for seams of different thickness.
42. In a seam-rubbing machine, members constructed and arranged to guide a seam passing therebetween, a spring to press said members together, and a device to move them simultaneously away from each other against the pressure of the spring, to adjust the distance between the members for seams of different thickness.
43. In a seam-rubbing machine, in combination, seam-guiding members, a spring pressing said members together, a threaded stem between said members, and a threaded cone-shaped nut on said stem to cam the members apart against the pressure of the spring.
44. In a seam-rubbing machine, seam-rubbing means, a rotary work-support, mechanism to rotate said support, yielding means to maintain said support in an upper position, and a device to depress said support against the action of the yielding means, said mechanism being constructed and arranged to rotate the support both in the upper and in the depressed position.
45. In a seam-rubbing machine, seam-rubbing means, a rotary work-support, mechanism to rotate said support, yielding means to maintain said support in an upper position, a device to depress the support to permit withdrawing work thereover, and means adjustably to limit the upward movement under the influence of the yielding means.
46. In a seam-rubbing machine, in combination, a work-support, and a seam-flattening device comprising an ironing member and a rotary seam-pounding member carried thereby.
47. A seam-rubbing machine comprising, in combination, a rotatable yieldingly-mounted work-support, means for opening a seam and progressively guiding it to the work support, a rotary seam-beating device having a plurality of beating portions, and means to rotate said device to beat the seam on the support.
48. A seam-rubbing machine comprising, in combination, a rotatable work-support, means for opening a seam and progressively guiding it to the work-support, a rotary seam-beating device having a plurality of beating portions, and means to rotate said device to beat the seam on the support and feed it thereover.
49. A seam-rubbing machine comprising, in combination, a rotatable work support, means for opening a seam and progressively guiding it to the work support, a rotary shaft above the work support and parallel to the axis of rotation thereof, a drive member and a seam-beating device on the shaft, and gearing means engaging the drive member to drive the beating device to flatten the seam.
50. A seam-rubbing machine comprising, in combination, a rotatable work-support, a power-rotated seam-beating device having a plurality of projecting members rapidly and successively to engage a seam on the support to flatten it, and means including a plow and opposed guides for opening the seam and guiding it between the work-support and the seam-beating device.
51. In a seam-rubbing machine, in combination, a plow for opening a seam, a pair of relatively adjustable seam guides arranged to engage opposite margins of the material making up the unopened seam, and a single adjusting means for determining the positions of said guides relatively to each other.
52. In a seam-rubbing machine, in combination, pivoted seam guides arranged to engage opposite margins of the material constituting an unopened seam, means for yieldingly pressing said guides toward each other, and a rotatable screw threaded member having a conical portion constructed and arranged to spread the guides apart upon rotation of said member.

In testimony whereof I have signed my name to this specification.

FREDERICK M. FURBER.
